SHOE VAMP FILLER

Charles A. Volz, Chicago, Ill.

Application March 9, 1936, Serial No. 67,940

3 Claims. (Cl. 36—71)

This invention relates to a shoe vamp filler.

An object of the invention is to provide a shoe vamp filler which will prevent wrinkles in the upper of the shoe vamp from forming roughnesses on the inside of the shoe, and thus avoid the pinching and discomfort ordinarily caused by these wrinkles. Another object is to provide a shoe vamp filler of such character as to cause the passage of air therethrough, so that the shoe may be ventilated and the feet less likely to perspire.

It is common knowledge among all wearers of shoes that in the process of walking the shoe bends and the leather wrinkles or doubles on top where the bend takes place. This double or wrinkle presents a rough uneven surface, and the roughnesses and creases are ordinarily transmitted through the shoe lining and produce uneven pressures against the foot, causing great discomfort, blisters, callouses, etc.

Applicant has overcome this trouble by the use of a highly resilient rubber filler inserted between the upper and the lining of the vamp. This rubber filler yields to the roughnesses and wrinkles of the upper and transmits an even pressure on the inside of the shoe, thus providing greater comfort for the wearer. Numerous other advantages will appear as the specification proceeds.

In the drawing:

Figure 1 is a plan view of a preferred embodiment of the invention; Figure 2, a sectional view taken at line 2 of Figure 1, showing the relative position of the filler with respect to the upper and the lining of the shoe vamp; Figure 3, a sectional view showing the shape of the filler and lining when the upper is wrinkled; and Figure 4 a plan view of a modification showing a filler of different shape.

In the embodiment illustrated by Figures 1, 2, and 3, the filler is comprised of a front portion A, and wing portions W¹ and W². Over the surface of the filler are spaced perforations 10. As shown in Figures 2 and 3, the filler is disposed between the upper of the shoe vamp 11 and the lining 12.

The filler should be made of some highly resilient material, preferably sponge rubber, which has a reasonably close grain. If desired, other resilient materials may be used. Preferably, the filler should have an approximately convex cross section, having its center portion of greatest thickness, and both sides of the filler tapered toward the edges as illustrated in Figures 2 and 3. It has been found that a thickness of about $\frac{1}{8}$ inch at the center portion and $\frac{1}{16}$ inch or less at the edge is satisfactory, but other thicknesses may be used. The tapered or feather-edge may be

drawn to as thin an edge as may be practicable. In this preferred construction each side of the filler has a substantially convex surface and is tapered to provide the feather-edge.

The front portion A is adapted to be placed at the top part of the vamp, the edge 13 toward the toe of the shoe, and the edge 14 toward the laced portion of the shoe. The filler extends downwardly at its sides and the edges of the wings, 15 and 16, are sewed or lasted with the upper 10 at the welt of the shoe.

The size and spacing of perforations 10 may be as desired, but they should not be so large as to be perceptible through the shoe lining. In the illustrations given the perforations are shown only on the forward portion, but it is understood that they may be placed in any part of the filler as is desired.

The modification shown in Figure 4 is of the same general construction as the preferred embodiment with the exception that here the wings are omitted and the filler has a somewhat elliptical shape. This form of the invention is adapted to be placed below the lining. It is particularly adapted to be attached by means of adhesive or cement to the lining of the shoe, and is easily inserted by a repairman even after the shoe has been worn. Either the modification or the preferred form may be provided with a coating of adhesive for attachment to the upper or lining.

The operation of this filler is illustrated in Figure 3. As the shoe bends in walking the upper 11 becomes wrinkled and irregular. But the filler, being highly resilient, allows the depressions of the wrinkles to sink into the filler, and a practically even pressure is felt on the under side. Thus, the lining 12 is seen to follow the smooth outline of the under surface of the filler. When the wrinkles in the upper disappear, the filler then resumes its original shape as in Figure 2, still leaving the lining in smooth outline. It is understood, of course, that the filler is free to accommodate itself to the general curvature and outline of the vamp.

The perforations 10 aid in ventilating the shoe as it is worn. Without these perforations such a filler might cause the feet to perspire with the accompanying discomfort to the wearer. In the present construction the perforations provide passages for air and operate to cause air to move through the passages. As the filler is highly resilient and in the act of walking is alternately compressed and expanded, the volume of air within the perforations is being changed. This change

55

in the volume of air within the perforations tends to force a movement of the air and aid in the ventilation of the shoe.

By providing better ventilation this filler helps 5 to prevent perspiring of the feet and the accompanying burning discomfort. But in case the feet do perspire, a further advantage of the rubber filler is that it keeps the perspiration from reaching and attacking the upper of the shoe.

10 Another advantage obtained by this construction is that by allowing the wrinkles to be absorbed in the resilient material, the leather of the upper is not so hard pressed where it is doubled, which makes it less likely to crack and break at the 15 creases.

The foregoing description has been given for 20 clearness of understanding only, and no unnecessary limitations should be understood therefrom, but the appended claims should be construed as broadly as permissible, in view of the prior art.

I claim:

1. A shoe vamp filler comprising a piece of close grained sponge rubber adapted to be inserted be-

tween the upper and the lining of a shoe vamp, said rubber piece including a forward portion and wings projecting rearwardly from each side, said forward portion adapted to extend across the top of the vamp and said wings adapted to extend to the sides and soles of the shoe, said rubber piece being provided with spaced perforations and having a thickness of approximately $\frac{1}{8}$ inch near its center and less than $\frac{1}{16}$ inch at its edge.

2. In a shoe, having a vamp which includes an 10 upper and a lining, a piece of close-grained sponge rubber extending across the front portion of said vamp and between said upper and said lining, said rubber piece being attached to said vamp at the welt of the shoe.

15 3. In a shoe, a vamp comprising an upper and a lining, a piece of resilient rubber having a general shape the same as the upper of said vamp and providing wings extending along the sides of the vamp, the edges of said wings being sewed to said 20 upper and lining at the welt of the shoe.

CHARLES A. VOLZ.
